US0D1075260S

(12) **United States Design Patent** (10) **Patent No.:** **US D1,075,260 S**
(45) **Date of Patent:** **** May 20, 2025**

(54) **FOOTWEAR**

(71) Applicant: **Zappos IP LLC**, Las Vegas, NV (US)

(72) Inventors: **Susan Ann Proudman**, Lake Oswego, OR (US); **Brandon Charles Bjerre**, Manhattan, NY (US); **Sara Jaramillo Restrepo**, Medellin (CO)

(73) Assignee: **Zappos IP LLC**, Las Vegas, NV (US)

(**) Term: **15 Years**

(21) Appl. No.: **29/867,656**

(22) Filed: **Nov. 2, 2022**

(51) **LOC (15) Cl.** **02-04**

(52) **U.S. Cl.**

USPC **D2/972**

(58) **Field of Classification Search**

USPC D2/902-912, 947, 969-978
CPC A43B 1/00; A43B 1/02; A43B 1/05; A43B 1/10; A43B 1/0081; A43B 3/00; A43B 3/0036; A43B 5/00; A43B 5/06; A43B 5/10; A43B 9/00; A43B 9/04; A43B 13/00; A43B 13/14; A43B 15/00

(57) **CLAIM**

The ornamental design for footwear, as shown and described.

DESCRIPTION

FIG. 1 is a top, front, lateral perspective view of footwear, showing our new design;

FIG. 2 is a top, front, medial perspective view thereof;

FIG. 3 is a top, back, lateral perspective view thereof;

FIG. 4 is a top, back, medial perspective view thereof;

FIG. 5 is a lateral view thereof; and,

FIG. 6 is a medial view thereof.

The dashed broken lines depict portions of the footwear that form no part of the claimed design. The dot-dashed broken lines represent boundaries of the claimed design and form no part of the claimed design.

The claimed design includes the mirror images of the embodiment depicted that is not shown.

1 Claim, 6 Drawing Sheets

US D1,075,260 S
